UNITED STATES PATENT OFFICE.

PETER McGUIGAN, OF ASHLAND, WISCONSIN.

DESIGN FOR A TABLE-KNIFE.

SPECIFICATION forming part of Design No. 22,439, dated May 16, 1893.

Application filed April 5, 1893. Serial No. 469,209. Term of patent 14 years.

To all whom it may concern:

Be it known that I, PETER McGUIGAN, a citizen of the United States, residing at Ashland, in the county of Ashland and State of Wisconsin, have invented and produced a new and original Design for a Knife, of which the following is a specification.

Reference is to be had to the accompanying drawing forming a part of this specification, in which the figure represents, in perspective, a knife embodying my new design.

The design consists in the novel configuration of the knife blade as shown. Thus at

the back, a short distance from the handle the blade is broadened and concaved as at *a*, 15 the lines of the blade at the back narrowing both in front of and behind such concaved part, as shown.

I claim—

The design for a knife herein shown and described.

PETER McGUIGAN.
